(57) CLAIM

The ornamental design for a stuffed animal display bench, as shown and described.

DESCRIPTION

FIG. 1 is a front elevational view of the stuffed animal display bench of the present invention;

FIG. 2 is a rear elevational view of the stuffed animal display bench of FIG. 1;

FIG. 3 is a right side elevational view of the stuffed animal display bench of FIG. 1, the left view being a mirror image thereof;

FIG. 4 is a top plan view of the stuffed animal display bench of FIG. 1; and,

FIG. 5 is a bottom plan view of the stuffed animal display bench of FIG. 1.

The broken lines showing letters within an oval in FIGS. 1 and 4 are for illustrative purposes only and form no part of the claimed design.
